REAMER

David P. Blaker, Odessa, Tex.

Application March 1, 1952, Serial No. 274,354

10 Claims. (Cl. 255—73)

This invention relates to well drilling tools, and more particularly to a reamer for use in the rotary method of well drilling.

An important object of the invention is the provision of a reamer employing cutters of the roller type, and having means by which the cutters are securely but replaceably mounted on the reamer body.

Another object of the invention is to provide a reamer of the type referred to, wherein improved means is employed for securing and locking the cutter bearing blocks to the reamer body, whereby displacement of the bearings or the development of loose play between the parts of the structure, due to engagement of the reamer with objects in the well is effectively prevented.

A further object of the invention is the provision of a reamer of the type referred to, in which cutters of the roller type are employed, which cutters are mounted in bearing blocks received in recesses in the reamer body, and wedgedly secured in the recesses by removable wedges which are adjustably secured to the reamer body.

Another object of the invention is to provide a reamer structure of the type referred to wherein the cutters are mounted for rotation on shafts or pins which are in turn rotatably supported in bearing blocks carried by the cutter body, so that the pins as well as the cutters may rotate freely, thus effectively reducing the wear on the parts and prolonging the life of the tool, reducing the likelihood of sticking or jamming of the cutters and also rendering the parts more easily replaceable for purposes of maintenance and repair.

A still further object of the invention is the provision of a reamer of the type referred to, which is of simple design and rugged construction, capable of long withstanding the extreme conditions of hard usage and exposure to which such devices are customarily subjected, and in which the cutters, cutter bearing blocks and pins are easily removable and replaceable for purposes of maintenance and repair.

The principle of the invention, and its mode of operation, and application will best be understood from the following detailed description, constituting a specification of the same, when taken in conjunction with the accompanying drawings, wherein—

Figure 1 is a side elevational view of a reamer body constructed in accordance with the invention, showing a reamer in place thereon;

Figure 2 is a cross sectional view taken along the line 2—2 of Figure 1, looking in the direction indicated by the arrows;

Figure 3 is a side elevational view similar to that of Figure 1, showing the body of the reamer with the cutters and cutter bearings removed therefrom;

Figure 4 is a cross sectional view taken substantially along the line 4—4 of Figure 3, looking in the direction indicated by the arrows and rotated substantially 30° in a clockwise direction from Figure 4;

Figure 5 is a fragmentary cross-sectional view, on a somewhat enlarged scale, taken substantially along the line of 5—5 of Figure 1, looking in the direction indicated by the arrows;

Figure 6 is a fragmentary cross sectional view, taken

2

along the line of 6—6 of Figure 5, looking in the direction indicated by the arrows; and

Figure 7 is a fragmentary cross-sectional view, taken along the line 7—7 of Figure 5, looking in the direction indicated by the arrows.

Referring now to the drawings in greater detail, wherein like numerals of reference designate the same parts throughout the several views, the numeral 10 designates a reamer body, which is of generally cylindrical configuration, and is provided with a plurality of longitudinally-disposed, peripherally-spaced, cutter receiving recesses generally indicated at 14. The recesses 14 are preferably arcuate in cross section, as best indicated in Figure 2, and are of a size to accommodate roller cutters 16, therein, and to provide ample clearance between the outer peripheries of the cutters and the reamer body, so that the cutters may rotate freely in the recesses.

The cutter recesses 14 are extended at each end to provide bearing block recess portions 18, each of which has an undercut side wall 20, and is preferably formed with a flat bottom 22. Each of the end cutter bearing block recesses is also formed with a longitudinal side portion 23 and a lateral end portion 24 extending to a somewhat greater depth than the portions 18, as will be plainly seen from an inspection of Figures 3, 5 and 6.

A bearing block 28 is positioned in each of the recessed portions 18, in engagement with the side wall 20 and resting on the bottom 22 of the recess. The bearing blocks have tapered sides, corresponding to the undercut side wall 20 of the recess 18, and at the outer end the bearing blocks are formed with downwardly extending portions 30, extending into the laterally extending portions 24 of the bearing block recesses and engaging the opposite end walls of the bearing recesses, whereby the bearing blocks are securely locked in position against longitudinal movement with reference to the body of the reamer. Securing wedges 34 are positioned in the longitudinally extending portions of the bearing block recesses, in engagement with the side walls 26 thereof, and these wedges have tapered side walls 36, which correspond to and engage the adjacent side walls of the bearing blocks, to securely lock the bearing blocks in position on the body. The securing wedges are secured in place by means of the bolts 38, which extend through openings 39 in the wedges and are received in threaded openings 40 in the body beneath the bottoms of the recess portions or wedge sockets 23 as best shown in Figures 5 and 7 of the drawings.

As will be evident from an inspection of Figures 5 and 7, the wedges 38 are somewhat shorter than the depth of the recess portions or sockets 23 so that the wedges may be drawn inwardly by tightening the bolts 38, in order to securely lock the bearing blocks in position, and prevent any loose play of the bearing block in the body.

The securing wedges 34 are each provided with an internally threaded opening 42, for the reception of a bolt 44, or other suitable tool, which is adapted to engage the bottom of the recess portion 23 for the purpose of forcing the wedges out of the recesses, in the event of sticking of the wedges, when it is desired to remove the same, in order to remove and replace the bearing blocks 28.

The roller cutters 16 are carried on shafts or pins 46, which in turn are supported at their opposite ends in the bearing blocks 28. The cutters are preferably freely rotatable on the shafts 46, and these shafts are also mounted for free rotation in the bearing blocks, so that the cutters are floatingly supported and the cutters and shafts may rotate independently relative to the body, whereby any possibility of the cutters becoming stuck to the shafts or of the cutters failing to rotate is obvi-

ated. It will also be apparent that by providing for the free rotation of the cutters on the shafts and for free rotation of the shafts in the bearing blocks, wear between the parts is greatly reduced and takes place uniformly thus substantially increasing the useful life of the tool.

In assembling the reamer, the roller cutters with their shafts 46 are assembled with the bearing blocks 28, and the bearing blocks are seated in the recesses or bearing seats 18, with the extension 30 of the blocks extending into the lateral recess portions 24. The wedges 34 are then inserted in the recess portions or wedge sockets 23, with the tapered side walls 36 of the wedges in engagement with the adjacent side walls of the bearing blocks, and the bolts 38 are then inserted through the openings 39 and screwed into the openings 40 in the body, until the wedges are moved into secure locking engagement with the bearing blocks. Because of the undercut side walls 20 of the bearing block recesses or seats, and the tapering side walls of the block, as well as the tapering side walls 36 of the wedges, the blocks are securely held in the recesses, against outward displacement relative to the body. Also the engagement of the extension 30 of the bearing blocks in the laterally extending recess portions 24, the bearing blocks are securely held against longitudinal movement relative to the body, and in the event that the bearing blocks or the cutters should engage any object in the well bore, such as irregularities in the well casing, or the ends of sections of the well casing where the same are coupled together, during inserting or removal of the reamer from the well, the blocks are prevented from being knocked loose from the body, or from being displaced longitudinally into wedging engagement with the cutters, whereby the cutters might become jammed in the recesses, and be prevented from rotating freely during the reaming operation.

It will, of course, be understood that the cutters may be arranged in any suitable manner on the cutter body, and that the cutter recesses may be parallel to the axis of the body or at any desired or expedient angle or position relative thereto.

Should it become necessary to remove the cutters from the body, for purposes of replacement or repair, this can readily be accomplished by first removing the securing bolts 38, and in the event of sticking of the wedges in the wedge sockets, they can be removed therefrom by inserting the bolts 44 in the openings 42 in the wedges, whereupon the bolts 44 will engage the bottoms of the recess portions 23 and the wedges may then be forced out of the recesses.

It will thus be seen that the invention, as described above, provides a reamer of simple design and strong construction, which is easily manufactured, and whose parts are readily replaceable, in the event of excessive wear or damage.

The invention has been described herein in connection with a certain specific embodiment of the same, but it will be understood that this is intended by way of illustration only, and that numerous changes can be made in the construction and arrangement of the various parts, without departing from the spirit of the invention or the scope of the appended claims.

Having thus clearly shown and described the invention, what is claimed as new and desired to secure by Letters Patent is:

1. A reamer comprising an elongated body having an external cutter recess extending longitudinally thereof, said body having external cutter bearing recesses at each end of and opening into the cutter recess, each bearing recess having longitudinal side walls, a bottom wall and an end wall, one of said side walls being undercut, each bottom wall having a depression adjacent its end wall and extending laterally of said body and of said cutter recess, a bearing block in each bearing recess, said bearing blocks having an end wall abutting the end wall of the bearing

recess and a depending member received in said depression whereby the engagement of the end walls of the block and bearing recess and of the depending member in the depression will prevent longitudinal movement of the bearing block in either direction, but will permit lateral movement of the bearing block in the bearing recess and radial movement of the block into and therefrom, said bearing block having longitudinal side walls one of which is complementary to said undercut wall, a cutter journaled for free rotation upon said bearing blocks and disposed in said cutter recess, a longitudinal locking wedge for each bearing block disposed in a bearing recess to one side of said block, retaining means engaging the wedge and moving the same towards the bottom of the recess, another side wall of the bearing block cooperating with the wedge for simultaneously forcing the block laterally causing engagement of the inclined and undercut side-walls and for holding the block to the bottom of the bearing recess.

2. The combination of claim 1 including extracting means cooperating with the wedge and the bottom of the bearing recess for causing positive withdrawal of the wedge from the recess.

3. The combination of claim 1 wherein said blocks have bearing bores on their adjacent ends, means received in said bores supporting said cutter for rotation.

4. The combination of claim 1 wherein the cutter recess has a bottom wall, the bottom walls of said bearing recesses being of less depth than that of the cutter recess the bottom of said depressions being of greater depth than those of the bearing recesses.

5. The combination of claim 1 including extracting means cooperating with the wedge and the bottom of the bearing recess for causing positive withdrawal of the wedge from the recess, said retaining means and said extracting means each comprising a bolt.

6. The combination of claim 1 wherein each block has an inclined surface on its side wall which is remote from the undercut wall, said wedge having a locking surface complementary to and engaging the inclined surface.

7. The combination of claim 1 wherein each block has an inclined surface on its side wall which is remote from the undercut wall, said wedge having a locking surface complementary to and engaging the inclined surface, said inclined surface and said locking surface being coextensive.

8. The combination of claim 1 wherein each block has an inclined surface on its side wall which is remote from the undercut wall, said wedge having a locking surface complementary to and engaging the inclined surface, said inclined surface and said locking surface extending the entire length of the bearing block and the wedge respectively.

9. The combination of claim 1 wherein each block has an inclined surface on its side wall which is remote from the undercut wall, said wedge having a locking surface complementary to and engaging the inclined surface, said inclined surface and said locking surface extending the entire length of the bearing block and the wedge respectively, and being substantially coextensive.

10. The combination of claim 1 wherein each of said bearing recesses has an L-shaped trough in its bottom wall, one leg of the L-shaped trough comprising said depression and the other leg thereof lying laterally beyond the cutter recess and parallel thereto.
